UNITED STATES PATENT OFFICE.

CHARLES C. SELEY, OF ERIE, PENNSYLVANIA, ASSIGNOR TO GEORGE H. BARLOW AND JOSEPH J. DESMOND, OF CORRY, PENNSYLVANIA.

METHOD OF MAKING GARMENT STAYS.

Application filed July 27, 1923, Serial No. 654,130. Renewed December 7, 1925.

To all whom it may concern:

Be it known that I, CHARLES C. SELEY, a citizen of the United States, residing at Erie, in the county of Erie and State of Pennsylvania, have invented certain new and useful Improvements in a Method of Making Garment Stays; and I do hereby declare the following to be a full, clear, and exact description of the invention, such as will enable others skilled in the art to which it appertains to make and use the same, reference being had to the accompanying drawings, and to the letters of reference marked thereon, forming part of this specification.

This invention relates to method of manufacturing garment stays composed of a single wire having edge forming loops along each edge of the stay.

The features of this invention are herein-after described and pointed out and are illustrated in the accompanying drawings in which:

Figure 1 is a plan view of a fragment of a garment stay made in accordance with this invention;

Fig. 2 illustrates one of the operations in this invention;

Fig. 3 is an edgewise view of Fig. 2;

Fig. 4 is an end view of the wire braid before it has been operated upon by the operation shown in Figs. 2 and 3;

Fig. 5 is an enlarged view of the wire braid shown in Fig. 2, somewhat elongated; and

Fig. 6 is an illustrative view of the operation shown in Fig. 2.

In practicing this invention the wire is first put through a wire bending machine of the type shown and described in U. S. Patent No. 1,257,748, issued on my application February 28, 1918, which forms it into a ribbon as shown at A in Fig. 2, an end view (see Fig. 4) showing the wire in figure 8 form, the edge loops shingled over each other, thus placing in the wire, composing the loops, an initial torsional twist. I then insert the final end of the ribbon or braid

between press-rolls B and B' and pass it therebetween in a direction reversed or opposite to that in which it issued from the wire bending machine above mentioned, which turns the edge forming loops over backward, as illustrated in Figs. 3 and 6, the action of the rollers also elongating the braid by spacing the loops apart, as illustrated at A' in Fig. 2.

The pressing or twisting backward of the loops a, places a torsional twist in the wire, as indicated by the small arrows in Fig. 5, which extend from the loops a at one edge, to the loops a at the other edge of the stay. In Fig. 6, I have illustrated, by means of axial lines C, the movement of the loops from the position thereof, as formed by the wire bending machine, above referred to, to the position thereof, indicated by broken lines, after they have been bent backwardly. This backward bending or twisting of the loops a changes them from long pear-shaped loops, as shown at A in Fig. 2, to substantially circular eyes, thus increasing the initial torsional twist therein, and at the same time places a torsional twist in the diagonal wire between the loops or eyes a, as indicated by small arrows in Fig. 5, because, in the twisting backwardly of the loops at opposite edges of the stay strip, the wire is twisted substantially a half rotation.

The result of these operations is the increasing of the elasticity of the wire, thus rendering the finished stay, shown in Fig. 1, very elastic in all directions, and not susceptible of becoming set when bent.

Having thus fully described my improved method of manufacturing garment stays, and illustrated a suitable means for practicing the same, what I claim as new, and desire to secure by Letters Patent is:

1. The method of forming a garment stay from a wire, consisting in bending the wire into a series of sinuous oppositely disposed helical loops, and then passing said bent wire between press rolls in a direction opposite to that in which the succession of loops

were formed whereby said loops are turned over backwards.

2. The method of forming a garment stay from a wire, consisting in bending the wire into a series of sinuous oppositely disposed helical loops whereby an initial tortional strain is placed in said wire, and then pass-

ing said bent wire between press rolls in a direction opposite to that in which the succession of loops were formed whereby said loops are turned over backwards thereby increasing the initial tortional strain. 10

In testimony whereof I affix my signature.

CHARLES C. SELEY.
